CLAIM

The ornamental design for a vehicle partition, as shown and described.

DESCRIPTION

FIG. 1 is a perspective view of the vehicle partition of the present invention as viewed from the rear;

FIG. 2 is a rear view of the vehicle partition of the present invention;

FIG. 3 is a front view of the vehicle partition of the present invention;

FIG. 4 is a left side of the vehicle partition of the present invention

FIG. 5 is a right side view of the vehicle partition of the present invention

FIG. 6 is a top view of the vehicle partition of the present invention; and,

FIG. 7 is a bottom view of the vehicle partition of the present invention.

The broken line showing is for the purpose of illustrating environmental subject matter and forms no part of the claimed design.

1 Claim, 5 Drawing Sheets
